DOORLOCK

Walter R. Schlage, San Francisco, Calif., assignor
to Schlage Lock Co., San Francisco, Calif., a
corporation of California

Application February 23, 1932, Serial No. 594,642

17 Claims. (Cl. 70—91)

This invention relates to door locks having inner and outer knobs with a key mechanism in the door knob, and particularly a manually actuated means in the inner knob for dogging the outer knob against rotation and for obstructing the key passage in the outer knob so as to prevent opening of the door by means of the outer knob, except by the insertion of an emergency key.

10 The object of the present invention is to generally improve and simplify the construction and operation of locks of the character described; to provide a door lock having inner and outer knobs with a key mechanism in the outer knob; a manually actuated means in the inner knob for dogging the outer knob against rotation, and for obstructing the key passage in the outer knob so as to prevent opening of the door from the exterior except by the insertion of an emergency key; to provide means for automatically shifting the dogging and obstructing member to permit the same to assume an intermediate position where the outer knob still remains dogged but where the key mechanism may be actuated by a number of keys to open the door; and further, to provide means actuated by rotation of the inner knob for releasing the dogging member so as to permit opening of the door from the exterior by rotation of the outer knob.

30 The door lock is shown by way of illustration in the accompanying drawings, in which—

Fig. 1 is a central vertical longitudinal section through the door lock, showing the dogging means and the key obstructing means in released position so that the latch bolt in the door may be retracted by rotation of either knob.

Fig. 2 is a cross section taken on line II—II of Fig. 1.

Fig. 3 is a cross section taken on line III—III of Fig. 1.

40 Fig. 4 is a plan section taken on line IV—IV of Fig. 1.

Fig. 5 is a perspective view of the inner knob spindle.

45 Fig. 6 is a perspective view of the button in the inner knob and the actuating rod attached thereto.

Fig. 7 is a perspective view partly broken away of the retractor.

50 Fig. 8 is a perspective view of the pin tumbler lock housing.

Fig. 9 is a perspective view of the lock indicator.

Fig. 10 is a perspective view of the coupler which couples the key rotating core of the pin tumbler lock and the key actuated spindle.

Fig. 11 is a perspective view of the outer knob spindle.

Fig. 12 is a perspective view of the key actuated spindle.

Fig. 13 is a perspective view of the dogging member.

Fig. 14 is a section similar to Fig. 1, said view showing the dogging member in dogging position and the keyway obstructing member in obstructing position.

Referring to the drawings in detail and particularly Figs. 1 and 2, A indicates in general a lock housing, in which is mounted a retractor B, and C indicates a housing which carries a latch bolt D, a retractor bar 2 to which the latch bolt 15 is secured and a spring 3 which surrounds the retractor bar and normally maintains the latch bolt in projected position. The lock housing indicated at A will hereinafter be referred to as the latch bolt actuating unit, and the housing B as 20 the latch bolt mechanism.

The housing A, as previously stated, encloses and supports the retractor B and it also forms a support for a pair of spindles E and F. Each spindle is provided with a knob, one knob being 25 indicated at 4 and the other at 5, the knob 4 will hereinafter be referred to as the outer knob and the knob 5 as the inner knob. The knobs are suitably secured with relation to their respective spindles and when either knob is rotated the co- 30 operating spindle will be rotated. The outer knob spindle is shown in perspective in Fig. 11 and the inner knob spindle is shown in perspective in Fig. 5.

It will be noted by referring to Figs. 5 and 11 35 that the inner end of each spindle is provided with a rollback member, one rollback member being indicated at 6 and the other at 6a. These rollback members engage the retractor B when the spindles are rotated and impart an endwise 40 movement to the retractor within the housing A, and during such movement also impart an endwise movement to the latch bolt D and cause retraction thereof. The retractor B is best shown in Figs. 1 and 7. It consists of spaced side plates 45 7 on the outer surfaces of which are formed shoulders 8 and 8a. The side plates are connected at their inner ends by a central cross bar 9 and the outer ends terminate in cross bars 10 which straddle and engage lugs 10a formed on 50 the inner end of the retractor bar 2. The rollback members formed on the inner ends of the respective spindles will engage the respective shoulders 8 and 8a on opposite sides of the retractor when the spindles are rotated, and it is through this en- 55

gagement that endwise movement is imparted to the retractor and to the retractor bar 2 so as to retract the latch bolt D; projection of the latch bolt being insured by the spring 3 which is compressed during the retracting movement.

The outer knob spindle E carries an interior spindle, shown in Figs. 1 and 12, and indicated by the numeral 11. This spindle will hereinafter be referred to as the key spindle, as it is

10 rotated by means of a key actuated mechanism only. This spindle is also provided with a roll-back member, such as shown at 6b, and when the spindle 11 is rotated by the key actuated mechanism the roll-back member 6b engages

15 the shoulder 8a and as such imparts endwise movement to the retractor and the latch bolt D, hence it is possible to retract the latch bolt either by the key actuated spindle 11 or by either of the knob actuated spindles E and F.

20 The door lock illustrated in the present instance is provided with a key actuated pin tumbler lock G, which is mounted in the outer knob, and it is provided with a push button H, which is mounted in the inner knob. The key actuated

25 pin tumbler mechanism is of standard construction and requires no particular explanation. It should suffice to say that it is provided with a rotatable core or cylinder member 12 in which is formed a key passage for the reception of a key, such as shown at 13. When this key is inserted, the core 12 may be rotated and during such rotation, movement is transmitted to rotate the key spindle

30 11 so as to cause retraction of the latch bolt D and opening of the door by means of a key. The connection between the core member 12 and the key spindle is best shown in Figs. 1, 8, 9, 10 and 12. The inner end of the core member projects through the inner end of the housing G and is provided with a cross slot 14. A cross bar 15, see Figs. 9 and 4, is mounted in this slot and this cross bar carries two pins indicated at 16 and 17. Holes are drilled through the core member 12 for the reception of these pins. A spring 11a cooperates with the pin 17 to normally maintain

35 the cross bar 15 in engagement with a pin 18 hereinafter to be described. The cross bar 15 functions as a key obstructing member, as will later be more fully understood, while the pin 16 functions as an indicator. The projecting end of

40 the core 12, as shown in Fig. 8, carries a coupling collar 19, see Fig. 10, this coupling collar being secured on the projecting end of the core in any suitable manner, for instance by a screw or by being soldered or otherwise secured. The coupling member is also provided with a cross slot, as shown at 20, and this is provided for the reception of a pair of lugs 21, see Fig. 12, formed on the outer end of the key spindle 11. The coupling member accordingly forms a coupling or connection between the core 12 and the key spindle 11, and when the core is rotated by means of the key, the key spindle will be rotated and the latch bolt D will be retracted to permit opening of the door by means of a key.

45 The inner knob 5, as previously stated, carries a push button H. This button is secured to an actuating rod generally indicated at K. The rod projects through the inner knob spindle F. It

50 projects through the retractor B as this is slotted, as shown in Fig. 7, to permit the actuating rod to pass therethrough, and the rod also extends through the spindles E and 11 and into the cross slot 20 formed in the coupling 19. In fact, it en-

55 gages the cross bar 15 and, as such, functions as

60

65

70

75

90 a means for moving the crossbar, or in other words the key obstructing member 15, into or out of key obstructing position, and it furthermore functions to move a dogging member L into and out of dogging position. The push button, together with the actuating bar K, attached thereto may assume any one of three positions; first, a released position such as shown in Fig. 1; secondly, a depressed position where it secures the key obstructing member in obstructing position, and the dogging member in dogging position; and third, it may assume an intermediate position where the key obstructing member is released but the dogging member remains dogged.

95 The dogging member has two functions: first, that of dogging or securing the outer knob and spindle against rotation; and secondly, that of securing the actuating rod and the push button H against rotation when either the inner or outer knob and cooperating spindles are rotated. The 100 dogging member is best illustrated in Figs. 1 and 13. It consists of a collar generally indicated at 24 which is slidably mounted within the key spindle. A central opening is formed in the collar and extends therethrough and this opening is 105 square, as shown at 25, to receive the square portion 25a of the actuating rod. The dogging collar is also provided with an extending lug 26 and this projects into a slot 26a formed in a spindle bearing 27. There are two spindle bearings, the 110 one indicated at 27 and the one indicated at 28. These bearings form a part of the lock housing A and they form bearings for the inner and outer knob spindles E and F. The lug 26, together with the dogging collar, is movable longitudinally of 115 the slot 26a and the lug may, accordingly, be moved into and out of engagement with a slot 29, see Fig. 11, formed in the inner end of the outer knob spindle E. The dogging collar is dogged against rotation at all times by means 120 of the lug 26 and the outer knob and spindle E are dogged by the lug 26 whenever it enters the slot 29 of the outer knob spindle.

125 The dogging member is shifted from one position to another by means of actuating rod K, 45 and as previously stated, it serves two main functions, first, that of dogging or locking the outer knob and spindle against rotation, and secondly, that of securing the actuating rod and the push button against rotation when 50 either knob and cooperating spindle is rotated. The dogging collar is always secured against rotation due to the fact that the lug 26 formed thereon projects into the slot 26a and, as the actuating rod is provided with a square portion 55 25a, the actuating rod and push button will also be secured against rotation.

60 In view of the fact that the actuating rod and the dogging member may assume three different positions, it is essential that means be provided for securing the actuating rod in the three different positions, as it is normally engaged by a spring 30 which tends to force the dogging member and the actuating rod in the direction of arrow a to assume released position, as shown in Fig. 1. The actuating rod and dogging member are held in released position by engagement of the dogging member with one side of the retractor, as shown in Fig. 1. The actuating rod and dogging member are secured 70 in intermediate position by means of a spring latch 32 which is adapted to engage a notch 33 in the actuating rod when the intermediate position is assumed, and the dogging member and the actuating rod are secured in their third 75

position when the keyway is obstructed and the outer knob and spindle are dogged, by means of a collar 35, see Fig. 14, which is engaged by a pair of latch arms 36.

5 The latch arms are best shown in Figs. 2 and 7. They are carried by the retractor B and they are pivotally mounted as at 37 between the side plates 7 of the retractor. Two sides of the housing A, indicated at 38 see Fig. 2, function as guideways for the retractor and a pair of springs 39 are interposed between the ends of these guideways and the latching arms 36. These springs form two functions, first, that of maintaining the retractor in the extended position shown in Fig. 2, and secondly, that of exerting pressure on the latch arms 36 to maintain them in engagement with the collar 35.

For the purpose of simplifying the description of the operation of the lock, it will be assumed that the lock is installed in a hotel. In such installations, three keys will be required, to-wit, a guest key, a master key, and an emergency key. Each guest occupying a room on a certain floor of a hotel will have his or her own key 25 to enter the room whenever desired. The maid on that particular floor will be provided with a master key which permits her to enter any room on that floor, and the hotel manager will have a single emergency key, which will fit any lock 30 on that or any other floor.

If a guest enters his or her room and desires absolute privacy, it is only necessary for the guest to depress the push button H after closing the door. Depression of the push button forces 35 the actuating rod K from the fully released position, shown in Fig. 1, to the fully locked position, shown in Fig. 14. During depression of the push button the actuating rod, see Fig. 14, is moved in the direction of arrow b and, during this 40 movement, the dogging member is moved from the position shown in Fig. 1 to the position shown in Fig. 14, thereby causing the lug 26 on the dogging member to enter the slot 29 of the outer knob spindle so as to dog and secure the 45 outer knob and spindle against rotation. It will also be noted that the inner end 18 of the actuating rod has moved the key obstructing member 15 from the position shown in Fig. 1 to that shown in Fig. 14, thereby obstructing full 50 insertion of guest or master keys and only permitting opening of the door by means of the emergency key. One thing more has been accomplished by the depression of the push button, to-wit, that of positioning the indicator 16, that 55 is, the end of the indicating pin 16 will in this instance project through the end of the core 12 and thus indicate to the maid on the floor that the guest is in the room and does not wish to be disturbed. In this position of the locking 60 mechanism the maid can not enter nor can any one except the manager, who has possession of the emergency key, and he will not use this key except in emergency cases, for instance sickness, accidents, or otherwise.

65 If the guest desires to leave the door open so that any one may enter without the use of a key, he merely rotates the inner knob 5. The inner knob 5 is always free to rotate and, when rotated, rotates the inner knob spindle F. During 70 such rotation, the roll-back member 6 will engage the shoulder 8 on the side of the retractor and the retractor will be moved inwardly from the position shown in Fig. 2. There are a pair of slots 36a in the latch arms 36. The collar 75

and engaged by the latching arms 36 but when the retractor is moved inwardly in the direction of arrow c, see Fig. 2, the latching arms 36 will move inwardly with the retractor and the collar 35 will ride out of the slots 36 and will thus be 5 automatically released and, when released, the dogging member, together with the actuating rod, will move back to the fully released position shown in Fig. 1 due to the tension of the spring 30. The latch 32 will not interfere with 10 the return movement of the dogging member and the actuating bar at this time, as it is secured to the inner knob spindle, and as such has been rotated with the inner knob spindle to a position where it is out of alignment with the 15 notch 33, hence it does not interfere with the return of the dogging member and the actuating rod to full released position shown in Fig. 1. Hence, by merely rotating the inner knob the guest completely unlocks the door, that is, releases the key obstructing member 15, the indicator 16, and the dogging member, and as such leaves the outer knob free for rotation to open the door.

If the guest desires to leave the room and at 25 the same time leave the door in a locked position so that the room may not be entered except by persons in authority, he first opens the door and then depresses the push button H, after which he walks out and merely slams or closes the door. 30 During depression of the push button he fully locks the door, as he moves the actuating rod and dogging member and the key obstructing member to the position shown in Fig. 14, but when he closes or slams the door he causes depression of the latch bolt D as this will engage 35 the striker plate of the door and as such will be depressed. During this depressing movement, the lugs 10a on the inner end of the retractor bar 2 enter between the latching arms 36 and thus 40 spread them apart a sufficient distance to release the collar 35 on the actuating rod. The actuating rod is thus released and would under normal conditions return to complete released position but, inasmuch as the inner knob and 45 spindle are not rotated, notch 33 in the actuating rod will align with the latch 32 and as such will be engaged by said latch and will be retained thereby in what is known as intermediate locking position. In this position the dogging member, 50 or in other words, the lug 26, still engages the slot 29 of the outer spindle, hence leaving the outer knob and spindle dogged but the key obstructing bar 15 is released and the door may accordingly be opened by the maid in possession of 55 the master key, and it may also be opened by the emergency key, and furthermore, by the guest when returning to the room. When the actuating rod and dogging member assume the intermediate position just described, the indicating 60 pin 16 is retracted and the maid in making the rounds of her floor can accordingly determine whether the guest is in or out and, as such, can enter and clean up the room during the absence of the guest. In fact, if the guest is in the room 65 and desires to have the maid enter to clean or restore order, it is only necessary for the guest to open the door, depress the button, and then again close the door. When he or she performs this operation the actuating bar and dogging member 70 will again assume the intermediate position where the outer knob is dogged against rotation but the indicating pin is retracted so that the maid will know that she may enter.

From the foregoing it will be noted that a lock 75

is provided whereby a guest may lock himself or herself in the room to insure complete privacy by merely depressing the button H. In this condition of the lock no one can enter except the manager in possession of the emergency key, and the maid will not attempt to enter as the indicating pin is projected and indicates that the guest does not wish to be disturbed; secondly, the guest may leave the door completely unlocked and 10 the outer knob free to rotate so that any one may enter without a key by merely rotating the inner knob; third, the guest may lock himself or herself in the room by causing the actuating bar and dogging mechanism to assume the intermediate 15 position described, in this position preventing entrance of any one except the maid, who is in possession of the master key, or the manager, who is in possession of the emergency key, and at the same time retracting the indicator to a position which indicates that the maid may enter; 20 fourth, the guest may lock the door when leaving the room by merely opening the door, depressing the button H, and then closing the door as he or she leaves the room. During the closing of the 25 door the latch bolt D is depressed and the dogging member and actuating bar will accordingly be automatically shifted to intermediate position, thereby retracting the indicating pin and the key obstructing bar, and furthermore, leaving the outer knob dogged so that no one can 30 enter except persons in authority, such as the guest, the maid, etc.

While certain features of the present invention are more or less specifically described, I wish 35 it understood that various changes may be resorted to within the scope of the appended claims. Similarly, that the materials and finish of the several parts employed may be such as the manufacturer may decide, or varying conditions or uses 40 may demand.

In Fig. 14, the emergency key is shown at 13a and in dotted lines is shown the maid's key 13. The dotted position of this key merely shows that it can not be fully inserted to operate the lock 45 when the push button is fully depressed, hence making it impossible to open the door with any key except the emergency key.

Having thus described my invention, what I claim and desire to secure by Letters Patent is—

50 1. In a door lock, a housing, a latch bolt, a retractor on each side of the housing, a key mechanism on the outer side for retracting the latch bolt, said key mechanism adapted to be actuated by a plurality of keys, means on the inner side 55 for rendering the outer retractor inoperative and simultaneously preventing full insertion in the key mechanism of said keys, and means actuated by closing of the door in which the lock is mounted for releasing a key obstructing means to permit full insertion of certain keys, said closing 60 of the door leaving the outer retractor inoperative.

2. In a door lock, a latch bolt, inner and outer 65 knob actuated means for independently retracting the latch bolt, an outer key actuated means for retracting the latch bolt, means for rendering both the outer knob and the key actuated means inoperative to prevent retraction of the latch bolt, and means whereby depression of the latch 70 bolt will restore the key actuated means for operation but leave the outer knob inoperative for operation.

3. In a door lock, a latch bolt, inner and outer 75 knob actuated means for independently retracting the latch bolt, outer key actuated means for

retracting the latch bolt, means for rendering both the outer knob and the key actuated means inoperative to prevent retraction of the latch bolt, means whereby depression of the latch bolt will restore the key actuated means for operation but leave the outer knob inoperative, and means whereby retraction of the latch bolt by the inner knob will restore the outer knob for operation.

4. In a door lock, a latch bolt, an inner and an 10 outer actuator for independently retracting the latch bolt, outer key actuated means for retracting the latch bolt, a push button, means whereby depression of the push button will render the outer latch bolt actuator and the outer key actuated means inoperative and means whereby operation of the inner actuator automatically releases the push button and renders the outer actuator 15 and the key actuated means operative.

5. In a door lock, a latch bolt, an inner and 20 an outer actuator for independently retracting the latch bolt, outer key actuated means for retracting the latch bolt, a push button, means whereby depression of the push button will render the outer latch bolt actuator and the outer key actuated means inoperative, and means whereby depression of the latch bolt will restore the key actuated means for operation but leave the outer latch bolt actuator inoperative.

6. In a door lock, a latch bolt, an inner and 30 an outer actuator for independently retracting the latch bolt, outer key actuated means for retracting the latch bolt, a push button, means whereby depression of the push button will render the outer latch bolt actuator and the outer key actuated means inoperative, means whereby depression of the latch bolt will restore the key actuated means for operation but leave the outer latch bolt actuator inoperative, and means whereby retraction of the latch bolt by the inner latch 40 bolt actuator will restore the outer latch bolt actuator for operation.

7. In a tumbler lock housing, a cylinder plug rotatable therein, said cylinder plug having a keyway for the reception of a key, a key shut-out 45 member carried by the cylinder plug and rotatable therewith, said key shut-out member being attached to the cylinder plug to prevent removal therefrom, and means operable independently of the cylinder plug for selectively positioning the 50 key shut-out member either to shut out the key or to permit full insertion of the key.

8. In a tumbler lock housing, a cylinder plug rotatable therein, said cylinder plug having a keyway for the reception of a key, a key shut-out 55 member carried by the cylinder plug and rotatable therewith, a lock indicator also carried by the cylinder plug and rotatable therewith, said key shut-out member being attached to the cylinder plug to prevent removal therefrom, and means operable independently of the cylinder plug for selectively positioning the key shut-out member either to shut out the key or to permit full insertion of the key, said means simultaneously moving the lock indicator to visibly indicate the position of the key shut-out member.

9. In a door lock, a latch bolt, inner and outer knob actuated means for independently retracting the latch bolt, an outer key actuated means for retracting the latch bolt, means for rendering both the outer knob and the key actuated means inoperative to prevent retraction of the latch bolt, and manually actuated means for restoring the key actuated means for operation but leaving the outer knob inoperative for operation.

10. In a door lock, a latch bolt, an inner and an outer actuator for independently retracting the latch bolt, key actuated means for retracting the latch bolt, a dogging member for dogging the outer actuator and the key actuated means against operation, means for securing the dogging member in one position where it renders the outer actuator and the key actuated means inoperative, means for moving the dogging member to a second position where the key actuated means is restored to operation but leaving the outer actuator inoperative, and means for moving the dogging member to a third and normal position where both the outer actuator and the key actuated means are rendered operative.

11. In a door lock, a latch bolt, an outer actuator for retracting the latch bolt, key actuated means for retracting the latch bolt, means operative from the inner end of the lock for rendering the outer actuator and the key actuating means inoperative, means whereby depression of the latch bolt will restore the key actuated means for operation but leave the outer actuator inoperative, and means operative from the inner end of the lock for restoring the outer actuator for operation.

12. In a door lock, a latch bolt, an outer actuator for retracting the latch bolt, key actuated means for retracting the latch bolt, a push rod operable from the inner side of the lock, a dogging member actuated by the push rod for dogging the outer actuator against operation, said push rod when operated simultaneously rendering the key actuated means inoperative, latch means for securing the push rod in a position where it dogs the outer latch actuator and renders the key actuated means inoperative, means for releasing said latch to cause the push rod to assume a second position where the outer actuator still remains dogged but the key actuated means is rendered operative, a second latch for securing the push rod in said second position, and means for releasing the second latch to cause the push rod to assume a third and normal position where the outer actuator is undogged and the key actuated means is operative.

13. In a door lock, a latch bolt, an inner and an outer actuator for independently retracting the latch bolt, key actuated means for retracting the latch bolt, a push rod operable from the inner side of the lock, a dogging member actuated by the push rod for dogging the outer actuator against operation, said push rod when operated

simultaneously rendering the key actuated means inoperative, latch means engageable with the push rod for securing the rod in a position where it dogs the outer latch actuator and renders the key actuated means inoperative, means operated by depression of the latch bolt for releasing said latch to cause the push rod to assume a second position where the outer actuator still remains dogged but the key actuated means is rendered inoperative, a second latch engageable with the push rod for securing the rod in said second position, and means operable by rotation of the inner actuator for releasing the second latch to cause the push rod to assume a third and normal position where the outer actuator is undogged and the key actuated means is operative.

14. In a lock, a latch bolt, a retractor on each side of the door whereby the latch bolt may be retracted, key operated mechanism on the outer side of the door whereby the latch bolt may be retracted, means on the inner side of the door for rendering the outer retractor and key mechanism inoperative, and means actuated by closing of the door for rendering the key mechanism operative but leaving the outer retractor inoperative.

15. In a lock, a latch bolt, a retractor on each side of the door whereby the latch bolt may be retracted, key operated mechanism on the outer side of the door whereby the latch bolt may be retracted, means on the inner side of the door for rendering the outer retractor and key mechanism inoperative, means actuated by closing of the door for rendering the key mechanism operative but leaving the outer retractor inoperative, and means actuated by operation of the inner retractor for rendering the outer retractor operative.

16. In a cylinder lock, the combination with a rotatable key plug having a key slot, of a key shut-out device slidably mounted in the inner end of the key plug and adapted to permit or prevent rotation of the key plug by a regular key, said key shut-out device being secured against separation from the key plug.

17. In a cylinder lock, the combination with a rotatable key plug having a key slot formed therein, of a key shut-out device slidably mounted within the key plug and adapted to permit or prevent full insertion of a regular key, said key shut-out device being secured against separation from the key plug.

WALTER R. SCHLAGE.
